ADALBERT K. FISCHER, OF PHILADELPHIA, PENNSYLVANIA, ASSIGNOR TO SCHUTTE & KOERTING COMPANY, OF PHILADELPHIA, PENNSYLVANIA, A CORPORATION OF PENNSYLVANIA.

CREMATORY.

1,156,398.

Specification of Letters Patent. Patented Oct. 12, 1915.

Application filed June 22, 1912. Serial No. 705,184.

To all whom it may concern:

Be it known that I, ADALBERT KOERTING FISCHER, a citizen of the United States, and resident of Philadelphia, in the county of Philadelphia and State of Pennsylvania, have invented certain new and useful Improvements in Crematories, of which the following is a specification.

This invention relates to crematories and comprises the arrangement of primary and secondary combustion chambers and an air supply chamber and system, all as herein fully set forth, whereby the cremation of organic material can be carried on in a practical and efficient manner, and it is particularly concerned with an arrangement of means for reducing the delays between operations due to the cooling and heating of the combustion chamber, thereby enabling the present apparatus to perform its intended function with substantial continuity of action.

In the accompanying illustration wherein I have shown more or less diagrammatically an apparatus exemplifying the present invention, Figure 1 is a vertical section of a cremation apparatus on the line 1—1 of Fig. 2; and Fig. 2 is a horizontal section of the same, looking down on line 2—2 of Fig. 1. In the showing of Fig. 1, element 1 is a primary combustion chamber having a roof 2 and rear wall 3. In its front wall 4 is an entrance opening closed by door 5, which may be of one or more sections and may be hinged. At its base the chamber is provided with hearth 6 upon which may rest a coffin or other receptacle 7. Tray 8 may be used for holding the ashes. At its front the primary chamber is provided with a down-take 9 bridged by slab 10 forming a platform in front of the door. The downtake communicates with a backwardly prolonged flue 11 terminating in a flue connection 12 at an angle to cause it to reverse the direction of flow of the gases. This flue connection opens obliquely into the secondary combustion chamber 13 which extends forwardly to the stack (not shown). Through the back wall of the primary chamber enters an air conduit or hood 14 having a ring valve 15 governing the supply of air thereto. Disposed within the hood is a gas or oil burner comprising a burner tube 16 into which air

may enter near its base through openings controlled by ring valve 17. Centrally 55 spaced within this tube is an oil-jet nozzle 18 supplied with oil through the header 19, valve 19^a, preheater 20, which may be a furnace of any suitable type, and a pipe leading from an oil storage tank 22. As 60 shown, the oil in this storage tank may be subjected to pressure by pipe 23, valved at 24, and leading from a tank 25 of compressed fluid such as carbon dioxid, but any other source of pressure can be used with 65 equal effect, as, for instance, an oil pump. The air conduit 14 and burner tube 16 both serve to admit air to the flame, as well as for other purposes later described, and they derive such air from the preliminary air 70 chamber 26 which is located immediately back of and adjacent to the two combustion chambers in heat-absorbing relation thereto, and which serves, among other things, as a preheater for the air introduced into the 75 combustion or crematory chambers. The secondary combustion chamber is provided with a ring-valved air conduit 30 inclosing a burner tube such as 16 and an oil nozzle such as 18, and also supplied with oil from 80 the header 19. This firing means may be identical with that first above described, and like that, is supplied with air from the chamber 26. Regulation of the burner mechanism may be made through openings 31, 85 provided with suitable closures in the rear wall of the preliminary heating chamber.

The air chamber 26, being common to both burner hoods, forms a large pressure chamber or equalizing reservoir of air surrounding both, and thus provides a desirable balance of air pressure on all sides of the air openings in the ring valves, which condition insures a long and symmetrical flame plume from each burner of uniform 90 character. Both flame plumes play in the same general direction, each being desirably axial of its chamber. Air is introduced to the heated chamber 26 and hence to both burners through the air pipe 27 from a fan 100 28 which is best provided with low and high speed driving connections 28^a and 28^b, respectively. Passage of air through the pipe is under the control of a damper 29, and such air becomes heated by delaying in the 105 chamber. The header and the oil pipes also

pass through the chamber and the oil becomes similarly preheated. Ordinarily the primary combustion chamber should be of considerably greater volume than the secondary, the secondary chamber being relatively narrow and tunnel-like. With these relative proportions the proper speed of the gases in the respective chambers is readily maintained. In the main chamber the speed 10 is naturally less than in the secondary, which is desirable, among other reasons, because there is thus little tendency for the ashes of the body being cremated to become scattered. The secondary chamber leads directly to the 15 stack or other discharge means, and the flow of the gases therein results partly from the pressure under which its burner operates and partly from the natural stack draft. On this account and also by reason of the 20 smaller diameter of the secondary chamber the gas velocity therein is materially greater than in the primary, and for this reason and because of the effectiveness of radiation from the permanently heated walls, combustion 25 becomes substantially perfect. Furthermore, the communication between the secondary chamber and the stack being as direct and free as possible, the combined effect of the described structure is to give 30 a somewhat lower pressure in the secondary chamber than in the primary chamber, and this differential pressure relation is maintained at whatever rate the burners are being driven, since said burners are fed with 35 fuel and air respectively from common pressure supplies.

The above described construction provides means for independently adjusting the quality and velocity of the flame delivered to 40 each combustion chamber and means for simultaneously varying the rate of driving of the burners.

As shown in Fig. 1, a portion 32 of the 45 roof of the secondary combustion chamber near the burner may form a partial baffle for the flame and the hot gases therefrom, giving an initial downward sweep against the floor after which they are deflected upward obliquely toward the top of the chamber where the gases from the upper chamber are entering the lower chamber, the two 50 streams of gases meeting at an angle approaching a right angle, and thoroughly mixing by the slight directional change thus produced without throttling effect. The 55 predominating sweep of the gases in the lower chamber is strongly toward the stack, so much so that the angular impingement of the burner flame and gases against the incoming gases does not materially lessen the 60 general action of the swiftly flowing gases as a whole in the lower chamber. But the angular impingement does produce a thorough intermingling of the gases at this 65 point, and the swirls and eddies thus pro-

duced continue as the gases rush on through the lower chamber and out to the stack. Such conditions are obviously eminently desirable for the most perfect combustion. It is to be understood that the conditions in the lower or secondary combustion chamber are maintained strongly oxidizing by admitting an excess of air through the valves of the lower burner and its conduit. A most intense combustion at very high temperatures 70 is thus obtained in the secondary chamber, a combustion sufficiently intense to consume even the most difficultly combustible gases formed in operations of this kind. 75

The apparatus may be constructed of fire 80 brick or other suitable refractory material incased, if desired, in an iron or steel shell, the partition wall between the preliminary air and combustion chambers being of such thickness as will transmit effectively the desired heat for preheating the oil and air. 85

In using the described apparatus, the fan having been started and the fuel in the fuel tank having been placed under pressure and admitted to the burners, the burners are 90 lighted and the desired character of flame obtained by suitably manipulating the ring valves controlling the admission of air from the common air supply chamber. The burner in the secondary combustion chamber 95 should be supplied with a larger proportion of air than that in the other chamber. This preliminary adjustment also establishes the optimum ratio between the rates 100 at which the burners in the respective combustion chambers are to be driven so as to give the desired suction of the gases from the primary into the secondary combustion chamber. This ratio established, the absolute speed or rate at which the burners are 105 to be driven can be varied for both burners simultaneously without altering the balanced ratio between conditions in the two chambers to a material or undesirable degree, such coincident speed variation being 110 obtained by varying the pressures on the common fuel and air supplies respectively, either separately or together and in the obvious manner. The early stages of the 115 cremation are, in the case of organic matter, substantially a distillation process, moisture and volatile combustible products being driven off and a gradual charring taking place. This is a heat absorbing operation, and were it not for the provision of the secondary combustion chamber, a large amount 120 of such volatile combustibles, many of which do not burn with extreme readiness, would escape combustion, partly on account of the attendant reduction in temperature. Partial combustion of these matters does however occur in the primary chamber, and the mixed gases, containing more or less free oxygen pass downwardly and rearwardly 125 through the connecting conduit where, by 130

reason of the reversals in direction to which the gases are subjected, any strata which may have been formed are broken up and the combustion continues. The converging 5 walls of the connecting passage aid in this mixing operation. The combustible matter still in the gases is consumed by the sharp oxidizing flame of the lower burner which strikes the gases as they enter obliquely 10 after two reversals in direction into the lower chamber. The gases issuing from the stack are colorless, odorless and otherwise inoffensive.

The non-volatile charred carbonaceous 15 residue from the first stages of the cremation burns off as the temperature of the primary chamber rises after the distillation stage, leaving a clean ash free of organic matter. The resulting gases may contain 20 products of incomplete combustion, but the subsequent treatment in the lower chamber eliminates these as before described.

After cremation is complete and the flame extinguished, access to the primary chamber 25 for the removal of the ashes is necessarily delayed until the temperature of the interior has fallen to a safe point. This delay, a period of idleness of the whole plant, is diminished to a minimum by the present 30 invention, by keeping the fan running and delivering air, through large chamber 26 and the burners into the primary and secondary combustion chambers. The chamber 26 will at that moment contain a large volume 35 of heated air which will first pass into the combustion chambers through the burners and burner sleeves and prevent sudden chilling of the highly heated walls of the apparatus such as might cause cracking 40 of the refractory lining. During the cooling stage the fan is advantageously run at considerably higher speed than during the combustion stage in order to produce a rapid 45 passage of tempered air in large volume through the crematory chambers. As further volumes of fresher and cooler air are sent into the heating chamber and thence into the combustion chambers, the temperature 50 continues to fall, without however allowing the heat gradient to exceed a safe limit, until the atmosphere within the chamber is cool enough to breathe with impunity, even though the walls of the chamber 55 may still be but partially cooled from their former high temperature. The ashes may then be removed and a new subject substituted whereupon the crematory will be ready for the next operation without the necessity of repeating the tedious process of 60 again heating up. It is an objection to the ordinary cremation process that whereas but from $\frac{1}{2}$ to $\frac{3}{4}$ hour may be required for the actual cremation, some three or four 65 hours are required to heat up in the first place, and three or four more to cool off,

after which heating up must be again gone through with. The present invention reduces this limitation on the capacity of the crematory to such extent as to render it substantially continuous in operation. 70

What I claim is:—

1. Cremation apparatus comprising a primary combustion hearth chamber, a secondary combustion chamber in communication and arranged in series therewith, flame producing means opening into each combustion chamber above the base thereof, means for supplying fluid fuel to said flame producing means and means for simultaneously varying in like degree the action of said flame 80 producing means. 75

2. Cremation apparatus comprising a hearth chamber, an auxiliary combustion chamber receiving effluent gases therefrom, an individual jet flame producing means for each chamber and a preheater chamber in heat-receiving relationship to both said chambers and arranged to deliver warmed air to both said flame producing means. 85

3. Cremation apparatus comprising a pair 90 of combustion chambers having individual axial flame-producing means and arranged in series, one such chamber being a hearth chamber and the other a flue chamber, a preheater in heat-receiving relation to both said combustion chambers and serving as a source of warm air supply to both said combustion chambers, and positively acting means for discharging warm air from said preheater through said flame producing 100 means. 95

4. In a cremation apparatus, a refractory walled crematory chamber, firing means therefor, an air heating chamber in heat receiving relationship thereto and controllable positively acting means for alternatively blowing air from said heating chamber to the firing means in relatively small volume and for blowing large volumes of rapidly moving air therefrom to said cremation 110 chamber to effect cooling of said chamber after a combustion operation. 105

5. In cremation apparatus, the combination with a refractory walled crematory chamber and a communicating preheater 115 chamber in heat-receiving relation thereto, of positively acting means for blowing a large volume of rapidly moving air through said preheater chamber and said crematory chamber, whereby said crematory chamber 120 may be cooled after a combustion operation by warmed air. 125

6. Cremation apparatus comprising a primary combustion chamber, a secondary combustion chamber in communication and arranged in series therewith, firing means for each combustion chamber, means for simultaneously supplying fluid fuel to said firing means, an air supply chamber in free communication with both said firing means and 130

- in heat-receiving relation to said combustion chambers, and means for supplying air under pressure to said air supply chamber.
7. Cremation apparatus comprising a primary combustion chamber, a secondary combustion chamber in communication therewith, firing means for each combustion chamber, means for supplying fluid fuel to said firing means, an air supply chamber in free communication with both said firing means and in heat-receiving relation to said combustion chambers, means for supplying air under pressure to said air supply chamber, and means for simultaneously varying the amount of fuel supplied to both said firing means.
8. Cremation apparatus comprising a primary combustion chamber, a secondary combustion chamber, a gas conduit connecting the said chambers, an air pressure and pre-heater chamber in heat-receiving relation to said combustion chambers, jet burners arranged to deliver flames into said combustion chambers and deriving warmed and compressed air for combustion from said air pressure chamber as a common source of supply, means for supplying air under pressure to said air pressure chamber, and simultaneously regulable fuel supply means for said burners.
9. Cremation apparatus comprising a primary combustion chamber, a secondary combustion chamber in communication therewith, an air supply chamber in heat-receiving relation to adjacent ends of said combustion chambers, jet burners mounted in such adjacent chamber ends to deliver flame jets into said chambers and arranged to take air from said air supply chamber, valved means for admitting air to said burners, means for supplying air to said air supply chamber at different pressures, and means for supplying fluid fuel to said burners.
10. In an apparatus for cremation, a combustion chamber having a suitable end wall, an air pressure chamber in heat-receiving relation to said wall, a jacket or casing positioned in said wall and opening into said combustion chamber and provided with adjustable means for admitting air from said pressure chamber, a jet burner mounted within said casing and arranged to deliver flame into said combustion chamber, means for supplying air under pressure to said pressure chamber, and fluid fuel supply means for said burner comprising a heating conduit for fluid fuel within said pressure chamber.
11. Cremation apparatus comprising a primary combustion chamber of relatively large diameter, a secondary combustion chamber of smaller diameter, a passage connecting said chambers, firing means for each chamber arranged to deliver flame lengthwise thereof, means for independently adjusting the quality and velocity of the flame delivered to each combustion chamber, and means for simultaneously varying the rate of driving said burners.
12. In a crematory apparatus, a refractory walled cremation chamber, a fluid fuel burner located in and passing through one wall thereof and having an air passage and a fuel passage, an air chamber having refractory walls and in heat receiving relation to said cremation chamber and in free communication with said air passage and positively acting means for forcing air into said chamber, said means being adapted to furnish different amounts of air to said air chamber at different times.
13. A crematory chamber having means for supporting the corpse therein, a fuel-burning mechanism for heating said chamber including a source of air under pressure and means for artificially cooling such chamber comprising positively acting means for increasing the volume of air delivered to and forced through the burner mechanism to the chamber.
14. A crematory chamber of the kind described, having means for supporting a corpse therein, a fuel burning mechanism for heating the chamber, means for conducting air to such burner mechanism in amount suited to accommodate the maximum combustion therein, and means for artificially cooling the said chamber comprising a controllable power actuated source of air pressure operable to deliver air to said chamber in volume exceeding the maximum combustion requirements of the said burner mechanism.
- In testimony whereof, I have signed this specification in the presence of two witnesses. 105
